UNITED STATES PATENT OFFICE.

FREDERICK WINK, OF PHILADELPHIA, PENNSYLVANIA, ASSIGNOR TO
THOMAS DOLAN AND R. WILLIAMS, JR., OF SAME PLACE.

DESIGN FOR SHAWL.

Specification forming part of Design No. **6,394**, dated February 11, 1873.

To all whom it may concern:.

Be it known that I, FREDERICK WINK, of the city and county of Philadelphia, State of Pennsylvania, have invented a Design for Shawl-Pattern, of which the following is a specification:

The principal features of the design, which is clearly illustrated in the drawing, are the alternate wide and narrow stripes A and B, separated by the plain body C. The narrow stripe B is composed of a series of plain parallel ribs, arranged as shown, and the wide stripe A is similarly made up, except that its members are in greater number and variety, and of greater width. The stripe A has also

a shaded portion, a, near the border composed of parallel ribs blended into each other, as shown.

Irrespective of the colors employed, I claim—

1. The design for the stripe A, as shown.
2. The design for the whole pattern, including the stripes A and B.

In testimony whereof I have signed my name to this specification in the presence of two subscribing witnesses.

FRED. WINK.

Witnesses:

WM. A. STEEL,
HUBERT HOWSON.
